Attorney

UNITED STATES PATENT OFFICE.

WILLIAM J. EICHENBERG, OF TOLEDO, OHIO, ASSIGNOR TO INDUSTRIAL RESEARCH CORPORATION, OF TOLEDO, OHIO, A CORPORATION OF DELAWARE.

DRIVING MECHANISM.

Application filed July 22, 1918. Serial No. 246,140.

To all whom it may concern:

Be it known that I, WILLIAM J. EICHENBERG, a citizen of the United States, residing at Toledo, county of Lucas, and State of Ohio, have invented certain new and useful Improvements in Driving Mechanism, of which I declare the following to be a full, clear, and exact description.

This invention relates to a drive mechanism adapted for insertion between an electric motor and the crank shaft of an internal combustion engine, and has specific utility when employed for starting purposes.

The principal object of the invention is to utilize a type of driving mechanism in which the resilient element thereof is subjected to compressional strains only.

Another object is to provide a driving mechanism in which the resilient member is outside the direct line of power transmission.

A further object is to employ a type of drive wherein engagement and disengagement with the engine is made in an entirely automatic way.

Further objects, and objects relating to economies of manufacture and details of construction, will definitely appear from the detailed description to follow.

I accomplish the objects of my invention by the devices shown in the accompanying drawing; my invention is clearly defined and pointed out in the appended claims.

A structure showing a preferred embodiment of my invention is illustrated in the accompanying drawings, forming a part of this specification, in which:—

Figure I shows a driving mechanism partly in section with the operative elements in disengagement; and

Figure II shows a sectional view of the mechanism in operative position.

Similar reference numerals refer to similar parts throughout the several views.

Referring to the numbered parts of the drawing, I have shown a portion 1 of an electric motor, which is preferably of the series type, this type having been found advantageous for starting purposes. A casing 50 is formed with a bearing 2, which is adapted to receive the motor shaft 3 which extends outwardly therefrom. The movable driving element consists of a sleeve 4, the outer surface of which is cut to form a worm

55 gear as indicated at 5. For a portion of its

length, the motor shaft is channeled longitudinally as indicated at 6, Figure II, and by means of the key 7, securely attached to the inner surface of the sleeve. The sleeve has axial movement along the motor shaft, and at the same time, is prevented from having relative rotational movement with the shaft through the employment of this key connection.

Secured to the bearing of the motor 1 by means of a machine screw 8, is a metal strip 9, which terminates at its outer or free end in a hook 10, which is formed by stamping a straight walled V-shaped groove 11 across the end of the strip, parallel to the end. The offset portion of the groove or hook is designed to ride between the threads of the worm gear, so that rotation of this gear will tend to force it axially along the shaft. In addition, the strip 9 has such a resiliency that when the sleeve is forced inwardly toward the motor, the inclined base of the groove 11 will ride over the threads of the worm gear, and inasmuch as the outer incline of the groove 11 is less than that of the inner incline, an outward movement of the sleeve operates against greater force than the inner movement, thereby tending to hold the sleeve adjacent the motor, unless a rotational force is applied to the motor shaft.

The outer end of the motor shaft is fitted with a terminal plate 12, the edges of which are inturned as shown at 13, Figure I, to form a shallow cup. This plate 12 is rigidly secured to the shaft by means of a pin 14, and is adapted to have rotational movement in the bearing 14' fixed to the motor or engine casing. Adjacent the end plate 12 is mounted a sleeve 15, which is slidable upon the motor shaft. And near the inner end of this sleeve an annular flange 16 is formed, the edges 17 of which are out-turned to form a second shallow cup. The shallow cups formed by the flange edges 13 and 17 form terminal bearings for a coil compression spring 18, which serves as the resilient element of the motor drive. The outer end of the sleeve 15 terminates at such a point that it contacts with the plate 12 when the spring is subjected to the maximum of compression.

The driven element is illustrated by a section 19 of a gear which is adapted to have direct connection with the crank shaft of an internal combustion engine. According to

common usage, this gear ordinarily takes the form of the fly wheel of the engine, so that the drive from the motor shaft passes directly from the worm gear to the fly wheel of the internal combustion engine.

As previously indicated, the normal inoperative position of the motor drive is as indicated in Figure I of the drawing, with the grooved portion of the spring in engagement with the threads of the gear. Rotation of the shaft, as indicated by the small curved arrow, will cause the grooved end of the metal strip 9 to screw along the thread of the sleeve, forcing the sleeve outward axially along the shaft. This outward movement continues until the grooved end of the strip 9 is completely out of the threaded portion of the sleeve, at which time the thread of the sleeve will have meshed with the teeth of the gear wheel 19, and as the sleeve is in full rotation with the motor shaft, the sleeve will screw itself outwardly along the shaft until its outer end comes in contact with the inner end of the sleeve 15. As the thread of the sleeve is, at this point, fully in mesh with the teeth of the gear 19, the continued rotation of the motor shaft will force the sleeve still further outwardly against the expansive force of the spring 18. There is evidently a limit of the degree of compression which the spring will receive, namely the point in which the outer end of the sleeve 15 comes in contact with the plate 12, but before this point has been reached, the expansive force of the spring will have reached such a value that the inertia of the gear 19 will have been overcome, and the motor will drive through the sleeve to the engine, as through a worm drive, thereby enabling the engine to start and operate under its own power. It is of course apparent that the variation of load during starting, due to the engine pistons going over compression points, is yeldingly taken up by the spring, thus permitting a relatively smooth power transmission in which the sleeve 4 is held in constant contact with spring sleeve 15. As soon as the engine takes up its own cycle of operation, inasmuch as the peripheral speed of the gear 19 greatly exceeds that of the speed imparted to it by the motor, there will be a tendency to force the sleeve inwardly toward the motor; and as the sleeve is free to slide upon the motor shaft the sleeve moves forcibly inwardly toward the motor, the edges of the thread riding under the grooved end of the spring plate 9.

It should be particularly noted that there is no direct drive in the motor through the resilient element 18, but that the spring serves merely as a shock absorbing means for taking up a portion of the rotational force of the motor at starting, thereby preventing costly breakage of the movable parts. Attention is also directed to the sim-

plicity of operation and the small number of parts, and also to the full automatic nature of the engagements and disengagements of the movable parts.

I am aware that the specific embodiment of my invention herein shown and described is susceptible of considerable variation without departing from the spirit of my invention, and, therefore, I desire to claim the same broadly as well as specifically, as indicated by the appended claims.

Having thus described my invention, what I claim as new and desire to secure by Letters Patent, is:

1. In a motor drive for internal combustion engines, the combination of an engine gear; a starter shaft positioned adjacent said engine gear; a key-way in the shaft; a sleeve keyed to the shaft and having sliding axial movement relative to the shaft; a thread on said sleeve adapted to mesh with the engine gear; means in mesh with the thread for holding the sleeve in inoperative position; and means for absorbing the jar incident to the initial application of force to the engine gear.

2. In a motor drive for internal combustion engines, the combination of an engine gear; a starter shaft positioned adjacent said engine gear; a key-way in the shaft; a sleeve keyed to the shaft and having sliding axial movement relative to the shaft; a thread on said sleeve; means in mesh with the thread for holding the sleeve in inoperative position, and for moving the sleeve into operative position relative to the engine gear; and means for absorbing the jar incident to the initial application of force to the engine gear.

3. In a motor drive for internal combustion engines, the combination of an engine gear; a starter shaft positioned adjacent said engine gear; a key-way in the shaft; a sleeve keyed to the shaft and having sliding axial movement relative to the shaft; a thread on said sleeve; means in mesh with the thread for holding the sleeve in inoperative position, and for moving the sleeve into operative position relative to the engine gear when the starter shaft revolves; a second sleeve freely movable on the shaft and adapted to have contact with the screw sleeve when in operative position; and a spring operative to oppose a sliding movement of said second sleeve.

4. In an engine starting mechanism, the combination of a power shaft; an externally threaded sleeve secured to said shaft, slidably and non-rotatably relative thereto; and single means for moving the threaded sleeve into operative position prior to starting and for retaining the sleeve in inoperative position subsequent to starting.

5. In an engine starting mechanism, the combination of a power shaft; an exter-

nally threaded sleeve secured to said shaft, 5
slidably and non-rotatably relative thereto; and single automatic means for moving the threaded sleeve into operative position prior to starting and for retaining the sleeve in inoperative position subsequent to starting.

6. In an engine starting mechanism, the combination of a power shaft; an externally threaded sleeve secured to said shaft, slidably and non-rotatably relative thereto; single means for moving the threaded sleeve into operative position prior to starting and for retaining the sleeve in inoperative position subsequent to starting; and additional 15 means for yieldingly engaging the sleeve when in operative position.

7. In an engine starting mechanism, the combination of a power shaft; an externally threaded sleeve secured to said shaft, slidably and non-rotatably relative thereto; sin-

gle automatic means for moving the threaded sleeve into operative position prior to starting and for retaining the sleeve in inoperative position subsequent to starting; and additional means for yieldingly engag- 25 ing the sleeve when in operative position.

8. A starter mechanism comprising, a gear adapted to be fixed to the shaft of an engine, a motor, a second gear slidable on and rotatable with the shaft of the motor, 30 and a lug adapted to engage the second gear for feeding the same into mesh with the first gear when the motor shaft is rotated in a predetermined direction, and for holding the same out of mesh with the first 35 gear when the latter is rotated in a predetermined direction.

In testimony whereof, I affix my signature.

WILLIAM J. EICHENBERG.
